Primary Examiner — T. Chase Nelson*Assistant Examiner* — Ania K Dworzecka(74) *Attorney, Agent, or Firm* — Muncy, Geissler, Olds & Lowe, PLLC(57) **CLAIM**

The ornamental design for a lamination for an electric motor, as shown and described.

DESCRIPTION

FIG. 1 is a perspective view of our new design for a lamination for an electric motor; and,
 FIG. 2 is a top view of our new design, the bottom view being the same.

1 Claim, 1 Drawing Sheet**FIG. 1**

FIG. 2
